UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed June 14, 1924. Serial No. 719,922.

This invention aims to provide an improved separable fastener.

In the drawings, which illustrate a preferred embodiment of my invention:—

6 Figure 1 is a front elevation of a preferred form of fastener;

Fig. 2 is a front elevation of the socket as attached to a support;

10 Fig. 3 is a section on the line 3—3 of Fig. 1, being partly in elevation;

Fig. 4 is a section on the line 4—4 of Fig. 1, showing the stud in unlocked position prior to disengagement from the socket;

15 Fig. 5 is a rear elevation of the stud;

Fig. 6 is a section on the line 6—6 of Fig. 4; and

Fig. 7 is a section on the line 7—7 of Fig. 4.

20 Referring to the preferred form of my invention, I have shown a stud attached to a curtain 1 and a socket attached to the body 2 of an automobile.

25 The preferred form of stud is provided with a socket-engaging part 3 having longitudinal slits 4 to permit contraction and expansion of the head when engaging and disengaging a socket. The socket-engaging part 3 is preferably pressed from the back plate 5 and is secured to that side of the curtain adjacent the socket by means of prongs 6 struck up from the periphery of an attaching plate 7. These prongs pierce the curtain and are thereafter curled outwardly and downwardly by an anvil portion 8 integral with a front plate at the opposite sides of the curtain 1.

30 The attaching plate 7 also presents a tubular part 7' which surrounds the socket-engaging part 3 throughout a portion of its length to provide a support therefor.

35 A press-button 9 is located within the socket-engaging part 3 and held therein by prongs 10 thrown inwardly from the back plate 5. When the stud is assembled to the curtain 1, the press-button 9 is concealed from view by the curtain and is operated by pressing upon that part of the curtain which is exposed through an aperture 11 provided in the front plate. Thus the curtain is left 40 intact when the stud is attached thereto, thereby reducing to a minimum the possibility of tearing away from the stud.

45 The preferred form of socket is attached to the body 2 of an automobile by means of a screw 12 which is provided with a split

tongue 13 generally rectangular in cross-section and adapted to pass through an aperture of the same cross-sectional dimensions located at the inner end 14 of the socket casing 15. The split tongue is thereafter flattened against the inner surface of the end 14 of the casing, as best illustrated in Figs. 3, 4 and 7. When the screw is thus attached to the socket, there can be no relative movement of one part without a like movement of the other. The casing 15 presents at its outer end a flange 16 having a hexagonal periphery over which is clenched a portion of a front plate 17 thereby to secure the two parts together in a fixed relation to each other. The hexagonal periphery of the front plate provides a means for reception of a socket wrench or the like to attach the socket to the body of the car, there being a recess therein so that the casing 15 will be countersunk into the body of the car, as best illustrated in Figs. 3 and 4. The front plate 17 presents a stud-receiving aperture 18 therethrough, normally closed by a hat-shaped locking disc 19 urged into aperture-closing position by a spring 20.

50 The stud may be engaged with the socket by pressing upon the anvil part of the front plate, thereby forcing the socket-engaging part 3, of the stud, into the stud-receiving aperture 18. The head of the stud contracts as it enters the aperture and also engages the locking disc and urges it inwardly against the pressure of the spring 20, until the head expands, thereby permitting the crown part 55 of the locking disc to enter therein and engage the reversely bent portions 21 of the stud, thereby to prevent contraction of the head of the stud. Thus the stud is locked with the socket and cannot be separated therefrom by accidental strain exerted upon the curtain in any direction. In the position, as illustrated in Fig. 3, the locking disc has engaged and urged the press-button into its forward position.

55 Separation of the fastener may be effected by grasping the lower edge of the curtain and exerting a slight outward pull thereon, at the same time pressing the exposed part 100 of the curtain at the center of the front plate. Thus the press-button is urged inwardly and forces the crown part of the locking disc out of engagement with the reversely bent portions 21 of the stud thereby 105 permitting contraction and withdrawal 110

thereof from the stud-receiving aperture, as best illustrated in Fig. 4.

While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

I claim—

1. A separable fastener comprising, in combination, a socket presenting a stud-receiving aperture, a stud including a socket-engaging member for engagement with said aperture, means for securing said socket-engaging member to a stud-carrying medium, locking means forming part of the fastener assembly for locking said stud and socket together and press-button means located between the stud-carrying medium and the locking means, said press-button means operable by pressure exerted upon the stud-carrying medium adjacent said press-button means for shifting said locking means into unlocking position.

2. A separable fastener comprising, in combination, a socket presenting a stud-receiving aperture, a stud including a socket-engaging member for engagement with said aperture, means for securing said socket-engaging member to a stud-carrying medium, a spring-pressed locking part located in said socket for locking said stud and socket together and press-button means located on the same side of the stud-carrying medium as said socket-engaging member and operable by pressure exerted upon the stud-carrying medium adjacent said press-button means for shifting said spring-pressed locking part located in said socket into unlocking position.

3. A separable fastener comprising, in combination, a socket presenting a stud-receiving aperture, a cooperating stud having a head for engagement with said aperture, spring-pressed locking means located in said socket for locking said stud and socket together and a concealed press-button assembled with said stud and located entirely beyond the inner face of a stud support, said press button operable by pressing upon the outer face of the stud support to move said locking means into unlocked position thereby to permit separation of said stud from said socket.

4. A separable fastener comprising, in combination, a socket presenting a stud-receiving aperture, a cooperating stud secured to a flexible carrying medium and having a head contractible and expansible for engagement with said aperture, spring-pressed locking means for locking said stud and socket together and a concealed press-button located between said locking means and the

flexible carrying medium and manually operable to move said locking means into unlocked position thereby to permit separation of said stud from said socket, said spring-pressed locking means and press-button forming part of the fastener assembly.

5. A separable fastener comprising, in combination, a socket including a stud-receiving aperture and a spring-pressed closure plate normally closing said aperture, a cooperating stud having a head contractible and expansible for engagement with the wall surrounding said aperture, non-resilient locking means presented by said closure plate for locking said stud with said socket and a concealed press-button carried by said stud and manually operable to shift said locking means into unlocked position when separating said stud from said socket.

6. A fastener element secured to a flexible fabric presenting means at one side of the fabric for engagement with a cooperating fastener element, a press-button operative therein and concealed by the fabric and a plate at the opposite side of the fabric presenting an aperture therein for exposing a portion of the fabric adjacent said press-button to permit manual operation thereof by pressure exerted upon the exposed fabric.

7. A stud for a separable fastener including means for securing said stud to a flexible fabric, a socket-engaging part for engagement with a socket and a press-button concealed by said fabric and operable relative to said socket-engaging part by pressing upon said fabric adjacent said press-button.

8. A stud for a separable fastener including means for securing said stud to a flexible fabric, a contractible and expansible socket-engaging head, a press-button concealed by said fabric, and means for limiting the movement of said press-button relative to said head.

9. A socket for a separable fastener including a casing presenting a stud-receiving aperture at one end and a non-cylindrical aperture at the other end thereof, means for attaching said casing to a support and a tongue presented by said attaching means for passage through said non-cylindrical aperture to secure said attaching means to the casing, said tongue being non-cylindrical in cross-section for cooperation with the wall of the non-cylindrical aperture to prevent turning between the casing and the attaching means.

10. A socket for a separable fastener including a casing presenting a non-cylindrical aperture at one end thereof, a screw presenting a split tongue engageable with said aperture for securing said screw and casing in a fixed relation and tool-receiving means integral with said casing for reception of a

tool thereby to secure said casing to a support.

11. A flush type socket for a separable fastener including a casing presenting a closed end, a non-cylindrical aperture through said closed end and an attaching screw having a split tongue of substantially the same cross-section as said aperture, said tongue presented through said aperture and bent outwardly and downwardly into engagement with said closed end to secure said casing and attaching screw in fixed relation.

12. A fastener comprising, in combination, a socket for attachment to a rigid socket-carrying medium, the inner face of which is inaccessible, a stud projecting from and attached at that side of a flexible stud-carrying medium adjacent the socket-carrying medium, said stud presenting an expandable and contractible head, axially shiftable means forming part of the fastener assembly for locking said head in expanded position, and press button means assembled with said stud at the inner side of said curtain adjacent to the base of the stud for shifting said axially shiftable means out of locking position when pressure is applied to the outer face of said curtain.

13. A fastener comprising, in combination, a socket for attachment to a rigid socket-carrying medium, a stud projecting from and attached at that side of a flexible stud-carrying medium adjacent the socket-

carrying medium, said stud presenting an expandable and contractible head, shiftable means carried by said socket for locking said head in expanded position, and means at the inner side of said curtain for shifting said shiftable means out of locking position.

14. A fastener comprising, in combination, a socket for attachment to a rigid socket-carrying medium, a stud projecting from and attached at that side of a flexible stud-carrying medium adjacent the socket-carrying medium, said stud presenting an expandable and contractible head, shiftable means carried by and reciprocable relative to said socket for locking said head in expanded position, and means at the inner side of said curtain for shifting said shiftable means out of locking position.

15. A fastener comprising, in combination, a socket for attachment to a rigid socket-carrying medium, a stud projecting from the attached at that side of a flexible stud-carrying medium adjacent the socket-carrying medium, said stud presenting an expandable and contractible head, shiftable means carried by and reciprocable relative to said socket for locking said head in expanded position, and shiftable means at the inner side of said curtain for shifting said shiftable means out of locking position.

In testimony whereof, I have signed my name to this specification.

FRED S. CARR.

Certificate of Correction.

Patent No. 1,647,776.

Granted November 1, 1927, to

FRED S. CARR.

It is hereby certified that error appears in the printed specification of the above-numbered patent requiring correction as follows: Page 3, line 55, claim 15, for the word "the" read *and*; and that the said Letters Patent should be read with this correction therein that the same may conform to the record of the case in the Patent Office.

Signed and sealed this 6th day of December, A. D. 1927.

[**SEAL.**]

M. J. MOORE,
Acting Commissioner of Patents.
